Inventor

Zeno W. Day
By Frank M. Lehman
Attorney

UNITED STATES PATENT OFFICE.

ZENO W. DAY, OF NEWARK, NEW JERSEY.

MOLDING.

Application filed October 29, 1921. Serial No. 511,372.

To all whom it may concern:

Be it known that I, ZENO W. DAY, a citizen of the United States of America, and resident of Newark, in the county of Essex and State of New Jersey, have invented certain new and useful Improvements in Moldings, of which the following is a specification.

This invention relates to a molding for the suspension of bulletins, exhibits, plans, drawings and the like, and is intended for use as substitutes for tacks, nails, hooks or the like of a stationary character which are applied to papers or fabrics containing maps, printing or drawings which are to be exhibited.

An object of this invention is to provide novel means whereby hooks may be adjustably supported from the molding, in order that the hooks may be spaced apart different distances to suit particular requirements and to act as supports for bodies of different lengths and thus eliminate the driving of tacks or thumb tacks for this purpose. In using the term "body," the inventor wishes to be understood as meaning any paper, fabric or other element on which printing, illustration or drawing is carried. The invention is particularly adapted for use in school rooms and the like, and is used also as a molding across the top of black boards, bulletin boards and similar equipment.

In the commercial development of the invention, many uses will be found for it, but enough has been said, it is thought, to give a fair idea of its utility, it being the purpose of the inventor to provide an inexpensive bracket or base element adapted to be sanitary, as its structure enables it to be easily cleaned on the inside, and it also gives the proper finish, as it is capable of use in place of the molding usually fastened along the top of black boards. It may be anchored in a wall coating such as plaster during the construction of a building, the said device being capable of receiving slides carrying hooks or supports for bodies such as has been described.

With the foregoing and other objects in view, the invention consists in the details of construction, and in the arrangement and combination of parts to be hereinafter more fully set forth and claimed.

In describing the invention in detail, reference will be had to the accompanying drawings forming part of this application

wherein like characters denote corresponding parts in the several views, and in which—

Figure 1 illustrates a view in perspective of my improved molding including the adjustable hooks;

Figure 2 illustrates a front view of a fragment thereof;

Figure 3 illustrates an enlarged detailed sectional view on the line 3—3 of Fig. 2 and

Figure 4 illustrates an enlarged perspective view of the slide used in the bracket of the molding.

In carrying the invention into practice, I form a hollow molding of sheet metal which may be in the nature of an elongated bracket having a base 6, a back 5 at right angles to the base, and a top flange 7, the latter of which is preferably bent forwardly and downwardly from the top of the back, but terminating short of the front edge of the base to form an opening at the front of the said bracket. The base has a series of apertures 8 which may receive fastenings such as tacks or the like, being easily accessible through the opening at the front. The back wall of the bracket has a series of apertures 9 which may also receive fastenings when the bracket is to be secured against the face of a board or against the wall of a room, it being understood that the bracket shall be comparatively long, in order that the supporting elements may be spaced apart, to a greater or less extent, to engage bodies of different lengths.

The molding constitutes a bearing for the slides 10 which fit and slide in the bracket, it being the purpose of the inventor that the bodies of the slides shall be of the configuration of the channel in the bracket, and that shoulders 11 should be formed thereon which will constitute bearings to engage the edge of the flange 7, in order that undue oscillation of the slide will be prevented, since the shoulder will engage the edge of the flange and prevent it from turning laterally.

Each slide is provided with a hook 12, the shank 13 of which projects from the slide, and the hook may be of any appropriate configuration, preferably of that illustrated in the drawing, as such a hook has been found efficient in holding bodies such as maps, charts, bulletins and the like. The flange of the bracket is preferably provided with a notch or opening 14 of such size as to constitute a clearance for the reception of the

slides, and if the bracket is of great length such as would be necessary to reach from one end of a room to another, a plurality of notches might be supplied, in order that it will be unnecessary to move the slides a very great distance with relation to the bracket after they have been applied to the bracket. It will be apparent, however, that with the provision of the notches at points between the ends of the bracket, it will be unnecessary to insert the slides in the ends of the bracket and then to move them to positions between the ends of a room.

It is furthermore apparent that a device made in accordance with this invention will be of inexpensive construction, since the channel iron or bracket can be produced by the rolling processes now in common use, whereas the slides and hooks can be expeditiously manufactured.

This molding is adapted for new installations, and can also be used to replace the old fashioned wooden molding on the tops of black boards and partitions, presenting a finished appearance, being inconspicuous, easily attached and easily cleaned on the inside by running a cloth along the bracket. It is located where maps, bulletins and other papers used in school work can be suspended and changed at will at the proper and usual

place without the present disfiguration of the wood-work by tacks.

I claim:

1. A hollow molding formed of sheet metal bent to form a flat base, a rear wall perpendicular to the base, a top wall extending forwardly and downwardly from the top of the rear wall and terminating above and in rear of the front of the base so as to leave an opening whereby material can be swept from the base through the opening, and a slide fitting in the molding and projecting through the opening and having a hook extending beyond the molding, the base having openings for screws, said openings being disposed near the front edge of the base and thereby accessible from above.

2. A hollow sheet metal molding formed with a flat base, a rear wall at a right angle to the base and an inclined top wall extending from the top of the rear wall toward the front edge of the base but terminating short of the base to form a longitudinal slot, a slide fitting the slot and extending beyond and slightly above the front edge of the top wall, and a hook extending from the front of the slide and beyond the front of the molding.

ZENO W. DAY.
